INTERMITTENT AIR ACTUATED ACID FEEDER

Arthur E. Kittredge, Audubon, N. J., and Victor A. Rohlin, Glenside, Pa., assignors to Cochrane Corporation, Philadelphia, Pa., a corporation of Pennsylvania

Application January 4, 1938, Serial No. 183,318

3 Claims. (Cl. 221—95)

The general object of the present invention is to provide improved means for discharging a corrosive liquid, such as an acid, from a storage chamber or receptacle. A more specific object of the invention is to provide improved means for discharging acid or other corrosive liquid from a supply chamber or reservoir, in doses or charges, each of which constitute a small fraction only of the amount of the corrosive liquid which can be held in the storage reservoir. Other specific objects of the invention are to provide corrosive liquid feeding means, including a feed chamber so connected with the storage chamber and with discharge piping, that the corrosive liquid is caused to alternately pass into the feed chamber from the storage chamber, and from the feed chamber into the discharge piping, by increasing and reducing the air pressure acting on the liquid in the feed chamber, and to provide feeding means which includes no float or movable mechanism part in contact with the corrosive liquid, and has no valve or packing normally in contact with the corrosive liquid.

While not restricted to such use, the present invention was primarily devised, and is especially adapted, for use in neutralizing or eliminating excessive alkalinity in water given such alkalinity by a purifying treatment. For such use, it is necessary to closely proportion the amounts of added acid and of water to which the acid is added, and to accommodate a wide range of variation in the daily or hourly rate of water treatment. In such case, the air used in the acid feeding operation may be furnished by a motor driven blower which is started into operation to initiate each acid feeding operation, and which continues in operation for a period which should be long enough, at least, for the completion of the feeding operation. In so far as it directly concerns the operation of the feeding apparatus, it is immaterial whether the blower stops immediately at the end of each feeding operation, or continues in operation for an indefinite period thereafter, provided only that the operation is interrupted soon enough to permit the acid feed chamber to refill prior to the time when the next feeding operation should start. The blower driving motor may then be controlled by a controller mechanism actuated by a water meter to start the motor into operation, on the passage into or through the water purifying apparatus, of a predetermined amount of water, following the previous acid feeding operation, and including a timing mechanism for stopping the motor after a period of operation, not shorter than the maximum time period required for an acid feeding operation.

The various features of novelty which characterize the present invention are pointed out with

particularity in the claims annexed to and forming a part of this invention. For a better understanding of the invention, however, its advantages and specific objects attained with its use, reference should be had to the accompanying drawings and descriptive matter in which we have illustrated a preferred embodiment of the present invention.

Of the drawings:

Fig. 1 is a sectional elevation of a preferred embodiment of the present invention;

Fig. 2 is an elevation taken at right angles to Fig. 1, with parts broken away and in section;

Fig. 3 is a partial plan view, in section on the line 3—3 of Fig. 2;

Fig. 4 is a diagrammatic elevation, illustrating certain characteristic features of the apparatus shown in Figs. 1, 2, and 3, in the non-feeding condition of the apparatus;

Figs. 5 and 6 are views similar to Fig. 4, except that Fig. 5 shows liquid levels existing in an intermediate stage, and Fig. 6 shows liquid levels existing at the end of a feeding operation.

The general nature and mode of operation of our corrosive liquid feeding apparatus, is illustrated in the diagrammatic Figs. 4, 5, and 6. The apparatus shown in those figures comprises a corrosive liquid storage chamber, *a*, a measuring, or calibrated feed chamber cylinder *c*, and a U conduit connection between the chamber *a* and cylinder *c*, comprising vertical limbs *b* and *b'* connected at their lower ends. The limb *b* is formed by a pipe section extending downward from an outlet *a'* in the bottom wall of the chamber *a*. The limb *b'* is formed by a pipe section having its upper end opening into the chamber *c*. As shown, the level of the upper end of the pipe section *b* is slightly below the level of the upper end of the feed chamber cylinder *c* and slightly above the upper end of the pipe section *b'*. The connected lower ends of the pipe sections *b* and *b'* are below the minimum water level in the feed chamber. An uprising discharge pipe *d* is connected to the lower end of the cylinder *c*. The pipe *d* leads upward to a discharge outlet including a weir *e*, located at a level above the highest liquid level maintained in the chamber *a*. Liquid moving upward through the pipe *d*, flows over the weir *e* into the pipe *e'* through which the liquid fed is passed to the place at which it is used. As shown, the pipe *d* includes an upper vent portion *d'*, extending upward above the weir *e*, and open at its upper end to the atmosphere.

The space within the chamber *a*, above the liquid level therein, is in communication with the atmosphere through a vent connection *g*. A compressed air supply pipe *f* has a downwardly extending lower end portion which opens into the cylinder *c*, through the top wall of the lat-

ter. The pipe f is in communication with the air space in the chamber a through a restricted orifice f' . A portion f^2 of the pipe F between the orifice f' and the feed tank, is in the form of an inverted U, or gooseneck, so that corrosive liquid slugs, or condensate drops, in the pipe f , will drain either into the cylinder c , or into the supply reservoir a .

From the dose or charge measuring viewpoint, the cylinder c may be regarded as constituting the feed chamber, of the apparatus shown in Figs. 4, 5, and 6, but from an operative viewpoint, the feed chamber includes not only the cylinder c , but also the portion of the pipe f below the level of the liquid in the reservoir chamber a . With the air pressure in the pipe f equal to the pressure of the atmosphere, the liquid levels will be the same in the chamber a , in the delivery pipe d , and in the feed chamber, as shown in Fig. 4. The initial effect of a suitable increase in the pressure in the pipe f , is a backflow of liquid from the chamber c into the chamber a , through the U connection pipes b' and b , which continues until the liquid level in the chamber c is at the top of the pipe b' . Such return of liquid to the chamber a results in some actual increase in the height of the liquid level therein, but that increase is too small to be of significance, when the horizontal cross section of the chamber a is very much greater than that of the cylinder c , as is normal. While liquid is thus being returned from cylinder to chamber a , there is no significant increase in the hydrostatic pressure in the lower portion of the cylinder c , or height of liquid level in the discharge pipe d , though theoretically there is some such increase, because the head loss due to the flow through the pipes b and b' .

As the pressure in the pipe f is further increased, the liquid level in the pipe b' is lowered, and the liquid level in the pipe d is correspondingly raised until it reaches the level of the weir e , as shown in Fig. 5. As the pressure in the pipe f continues to increase, liquid is forced out of the feed chamber through the pipe d and over the weir e into the delivery piping e' . At the end of each normal feeding operation, the liquid levels in the chamber c and pipe b' will be as shown in Fig. 6, and the air pressure in the pipe f^2 will correspond to the liquid head h^4 .

For the attainment of the operative results and advantages contemplated, certain level relations are required in the apparatus shown in Figs. 4, 5, and 6. For one thing, the elevation, h' , of the weir e , above the level of the connection of the lower end of the pipe d to the feed chamber c must exceed the elevation, h^2 , of the maximum working liquid level in the tank a above the level of the connected lower ends of the portions b and b' of the U-tube feed connection. The elevation, h^3 , of the outlet a' of the chamber a , above the connected ends of the pipe portions b and b' should exceed the elevation, h^4 , of the level of the weir e , above the minimum level, c' , to which the liquid in the cylinder c is depressed by the air pressure in the pipe f . If at the end of each feeding operation, the same liquid level c' exists, and the air pressure in pipe f then corresponds to the liquid head h^4 , the quantity or dose of liquid discharged during each feeding operation will always be substantially the same, the volume of liquid so discharged being equal to the volume of the space within the cylinder c surrounding the pipe b' and extending between the level of the top of pipe b' , and the final low liquid level c' , subject to a normally insignificant variation

due to the effect of variations in level in the chamber a , on the amount of liquid in the pipe d at the beginning of the feeding operation.

With the levels related as shown and described, so that the distance h^3 is greater than the distance h^4 , the lower portion of the U conduit connection between the cylinder c and chamber a will be liquid sealed and air will not blow into the chamber a , through the tubes b' and b , unless the air pressure in the pipe f exceeds the predetermined normal maximum feeding pressure. With the described level relation in which the distance h' exceeds the distance h^2 , an abnormal increase in the air pressure in the pipe f will result in the air blowing out of the cylinder c , not through the discharge pipe d , but through the pipes b and b' into the chamber a , where it can do little damage.

The commercial embodiment of the invention shown in Figs. 1, 2, and 3, comprises parts A, A', B, B', C, D, D', E, E', F, F', F², and G, respectively similar or more or less analogous to the parts a, a', b, b', c, d, d', e, e', f, f', f², and g, of Figs. 4, 5, and 6. As shown, the chamber A is a compartment partitioned off in the upper portion 25 of a vertical tank-like structure A¹⁰. The feed chamber cylinder C is coaxial with the chamber A, and extends through its bottom wall outlet opening A'. The cylinder C is closed at its lower end, and has its upper end separated by an interposed head C² from an aligned tubular part C³, depending from the top wall of the chamber A. The U conduit connection between the chamber A and cylinder C comprises portions B and B'. The portion B' is formed by a tube mounted 35 within the cylinder C, and opening at its lower end through the bottom wall of that chamber, and opening at its upper end to the cylinder C at a level slightly below the bottom of the chamber A. The passage portion B comprises the annular space between the cylinder C and a surrounding tubular shell B³. The latter has a closed lower end, and has its upper end open and secured to the bottom wall of the chamber A in register with the outlet opening A' in that wall. The lower end of the part B³ is spaced beneath the lower end of the cylinder C to provide suitable communication between the portions B and B' of the U conduit connection between the chamber A and cylinder C.

The lower end of the air pressure pipe F is anchored in the head A² and communicates through a passage in the latter with the cylinder C. The gooseneck portion F² of the pipe F is above the top wall of the chamber A, and the port F' is formed in a portion A² of the top wall 55 of the tank A to which separate adjacent portions of the pipe F are connected. The body of the cylinder C, its ends, the tubular part C³ and the various pipes which are exposed to contact with the liquid may be made of suitable corrosive resistant material such as lead, and the shell B³ and the chamber A may be lead lined. As shown, a dome A³ mounted on the top wall of the chamber A, encloses and provides protection for adjacent portions of the piping. The pipe G extends vertically upward through the bottom wall of the chamber A, to the maximum desired liquid level in that chamber, and is adapted to serve as level limiting overflow connection to the chamber A, as well as to serve as an air vent or breather passage in normal operation.

In the apparatus shown in Figs. 1, 2, and 3, the air under pressure in the pipe F and chamber C, is supplied by a blower I driven by an 75

electric motor J. The outlet pipe I' of the blower I connects to the inlet of a liquid eliminating separator K, shown as provided with a valved drain K'. The air outlet of the latter is connected through a needle valve L, check valve L', pressure reducing valve M, and pressure regulator O, to the pipe F. The pressure chamber in the regulator O, is connected by a pipe P to a pressure gauge Q, the pointer position of which indicates the pressure in the pipe F and thereby the operative stage or condition of the apparatus.

The parts I, J, K, L, L', M, O, and Q may all be of standard commercial types and all those parts except the gauge Q are advantageously mounted within the shell A¹⁰.

The separator K serves the double purpose of a collector for compressor oil and an air chamber to smooth out or eliminate pressure surges in the air flowing away from the separator, when the air compressor is started into operation. The needle valve L between the separator K and reducing valve M definitely restricts the flow of air and requires the pressure within the separator K to be appreciably above atmospheric pressure when the air pump is delivering sufficient air to permit the regulator O to perform its regulating function. The flow of air past the needle valve thus begins gradually, notwithstanding the quick starting of the compressor into full speed operation when connected to the line. In passing through the intermediate operating stage shown in Fig. 5, the air pressure in the feed chamber needs to be but little above atmospheric pressure and appreciably below its final maximum value of the apparatus in the condition shown in Fig. 6. The rate at which oil will collect in the separator K is slow, and the oil may be withdrawn from time to time by manual adjustment of a cock in the drum K'.

In Fig. 1, J' represents a control mechanism for starting and stopping the motor J. As will be apparent, the motor may be started and stopped manually to effect the feeding operations above described, but for the use of the apparatus for some purposes, an automatic control of the starting and the stopping of the motor is advantageous. One use of the apparatus shown primarily contemplated is for the addition of sulphuric acid doses to boiler feed water which has passed through a zeolite filter (or softener) to avoid boiler steel embrittlement because of unsuitable sulphate to carbonate ratio in the boiler water and the contamination of the steam formed by CO₂, which the high alkalinity of the water would otherwise produce. For such use, the water treating rate may be such as to require an acid feeding operation every three or four minutes and that the compressor should operate for a minute or so at each feeding operation. In such use, a full charge of acid in the tank A may be proportioned to hold sufficient acid for a twelve hour operating period.

While in accordance with the provisions of the statutes, we have illustrated and described the best form of embodiment of our invention now known to us, it will be apparent to those skilled in the art that changes may be made in the form of the apparatus disclosed without departing from the spirit of our invention as set forth in the appended claims and that in some cases certain features of our invention may be used to advantage without a corresponding use of other features.

Having now described our invention, what we

claim as new and desire to secure by Letters Patent, is:

1. Liquid feeding apparatus comprising in combination, a liquid storage chamber having a lower liquid outlet, a feed chamber extending downward below the level of said outlet, a U conduit connection between said outlet and feed chamber comprising two limbs connected at their lower ends one of said limbs being connected at its upper end to said outlet and the upper end of the other limb opening to said feed chamber adjacent the upper end of the latter, a discharge pipe having its inlet end connected to the feed chamber at a level substantially below the level of said outlet and having an outlet located at a level above the maximum liquid level in said storage chamber, and means for subjecting the liquid in said feed chamber to an air pressure varying between that required to depress the liquid level in the feed chamber substantially below the upper end of said second limb and that at which the liquid levels in the reservoir and feed chamber equalize.

2. Liquid feeding apparatus comprising in combination, a liquid storage chamber having a lower liquid outlet, a feed chamber extending downward below the level of said outlet, a U conduit connection between said outlet and feed chamber comprising two limbs connected at their lower ends, one of said limbs being connected at its upper end to said outlet and the upper end of the other limb opening to said feed chamber adjacent the upper end of the latter, a discharge pipe having its inlet end connected to the feed chamber at a level substantially below the level of said outlet and having an outlet located at a level above the maximum liquid level in said storage chamber and means for subjecting the liquid in said feed chamber to an air pressure varying between that required to depress the liquid level in the feed chamber substantially below the upper end of said second limb and that at which the liquid levels in the reservoir and feed chamber will equalize, the difference in levels between the discharge pipe inlet and outlet being greater than the difference between the maximum water level in the storage chamber and the level of the connected lower ends of said limbs.

3. Liquid feeding apparatus comprising in combination, a liquid storage chamber having a lower liquid outlet, a feed chamber extending downward below the level of said outlet, a U conduit connection between said outlet and feed chamber comprising two limbs connected at their lower ends, one of said limbs being connected at its upper end to said outlet and the upper end of the other limb opening to said feed chamber adjacent the upper end of the latter, a discharge pipe having its inlet end connected to the feed chamber at a level substantially below the level of said outlet and having an outlet located at a level above the maximum liquid level in said storage chamber and means for passing air into said feed chamber to establish a predetermined air pressure therein and thereby depress the liquid level in the feed chamber below the upper end of said second limb, a distance less than that required to make the distance between the liquid level in the feed chamber and the discharge pipe outlet level, as great as the difference in levels between the storage chamber outlet and the connected lower ends of said two limbs.

ARTHUR E. KITTREDGE.
